UNITED STATES PATENT OFFICE.

ORLANDO F. CONIHE, OF BOSTON, MASSACHUSETTS.

VALVE.

SPECIFICATION forming part of Letters Patent No. 592,279, dated October 26, 1897.

Application filed May 14, 1897. Serial No. 636,541. (No model.)

To all whom it may concern:

Be it known that I, ORLANDO F. CONIHE, of Boston, (Charlestown,) in the county of Suffolk and State of Massachusetts, have invented certain new and useful Improvements in Valves; and I do hereby declare the following to be a full, clear, and exact description of the invention, such as will enable others skilled in the art to which it appertains to make and use the same.

My invention relates to new and useful improvements in locking-valves for gas or other pipes.

My invention consists in certain novel features of construction and combinations of parts hereinafter fully described and claimed.

In the accompanying drawings, Figure 1 is a side elevation of my device. Fig. 2 is a longitudinal section thereof with the valve closed; Fig. 3, a similar view with the valve open; Fig. 4, a top plan view of the washer-gate, and Fig. 5 a plan view of the bottom of the body portion of my valve.

In the accompanying drawings the numeral 1 indicates the body of the valve, which is provided with passages 2 and 3, having angle portions 4 and 5. A passage 6 extends through the center of the body portion. A valve-stem 7 is held to rotate within this passage and is provided with a pin 8, extending therethrough. Recesses 9 are made at predetermined points in the body of the valve and are adapted to receive the pin 8 when the stem is turned to a certain definite position. A cap 10 is attached to the upper part of the body portion, preferably by a screw-joint, as shown. Within this cap is a spring 11, normally holding the pin 8 in contact with the body of the valve. The lower portion of the valve is provided 40 with a valve-seat 12, and a recess extending approximately one-quarter way around the valve-seat is shown at 13. Upon this valve-seat is fitted a washer-gate 14, provided with a passage 15, having a contracted end, as shown. Passages 16 extend from this passage around the valve and meet in an opening 17, which is adapted to communicate with the egress-pipe 3. A lug 18 is held within the recess 13 and regulates the extent of motion 50 of the washer-gate. This washer-gate is further provided with a recess 19, in which is adapted to fit a lug 20 upon the stem 7 when

said stem is forced in against the action of the spring 11. A cap 21 is attached to the lower portion of the body of the valve and 55 serves to hold the washer-gate in its proper position.

In operation the gas or other fluid enters the valve by the pipe 2, passes downward when the valve is opened into the passage 15, thence 60 around the stem by means of the passages 16 into the opening 17, and from there into the egress-passage 3. It will be observed from the drawings that owing to the peculiarly contracted shape of the passage 15 the admission 65 of gas or other fluid can be controlled with extreme nicety. When it is desired to open the valve, the stem 7 is forced in against the action of the spring, thus raising the pin 8 out of the slots and forcing the projection 20 into 70 the recess 19. By turning the handle of the stem the washer-gate will now be revolved, and as much as may be necessary of the passage 15 caused to pass below the angle portion 4 of the passage 2. The spring 11, by holding 75 the pin 8 upon the upper portion of the body of the valve, will prevent the same from being turned without a considerable degree of force is exercised, and when the valve is shut off prevent it from being accidentally 80 opened. This valve, by reason of the small opening that is at first afforded, is especially adapted for use in pipes where the pressure is high and it is desired to gradually equalize 85 the pressure on both sides of the valve.

Having thus described my invention, what I claim as new, and desire to secure by Letters Patent, is—

1. In a valve, a body portion having passages extending therethrough, a stem, a washer-gate carried by said stem and provided with a passage having a contracted end portion, passages extending around the opening through which the stem passes and a recess communicating with said passages, and a cap extending from said washer-gate, substantially as described.

2. In a valve, a body portion having a central passage adapted to receive a valve-stem, extended end portions provided with valve-openings, a stem held to rotate within said central opening, a washer-gate having passages therein adapted to be rotated by said stem, a cap held upon the body portion of said valve

and adapted to retain the washer-gate in position, a cap extending over the upper portion of said stem having a recess therein, a spring held within said recess normally urging said stem outward, and a locking device adapted to hold said valve in closed position, substantially as described.

3. In a valve, a washer-gate having a central opening adapted to receive a valve-stem and provided with an entrance-passage having a contracted end, passages extending from

15 said entrance-passage around each side of the central opening, and an egress-passage with which said side passage communicates, substantially as described.

In testimony whereof I have signed this specification in the presence of two subscribing witnesses.

ORLANDO F. CONINE.
